RECORDED

UNITED STATES PATENT OFFICE.

MONTAGUE STANLEY NAPIER, OF LONDON, ENGLAND.

CURRENT-DISTRIBUTER FOR SPARKING DEVICES.

No. 866,212.

Specification of Letters Patent.

Patented Sept. 17, 1907.

Application filed September 26, 1904. Serial No. 226,050.

To all whom it may concern:

Be it known that I, MONTAGUE STANLEY NAPIER, engineer, a subject of the King of Great Britain and Ireland, residing at Acton Vale, London, W., England, 5 have invented certain new and useful Improvements in and Relating to Current-Distributors for Sparking Devices, of which the following is a specification.

The invention relates to electrical ignition apparatus for use with petrol motors and the like and has for its 10 object to provide efficient means for enabling more than one cylinder to be served from a single induction coil.

The invention consists in the combination of a high tension distributor with a low tension interrupter, the 15 shafts on which the two elements are mounted being geared together.

The invention further consists of the structural details of such a device to be hereinafter described and includes means whereby the sparks in the cylinders 20 can be accelerated or retarded.

Referring to the accompanying drawings which form part of the specification:—Figures 1 and 2 show front elevation and plan respectively of a form of four point ignition device according to the invention; Figs. 3 and 25 4 being sections on the lines A A and B B of Fig. 1 respectively; Fig. 5 shows a view of one of the high tension intermediate contact pieces; Fig. 5^a, being a corresponding section on the line C C of Fig. 5; Fig. 6 shows a cross sectional view of a form of six-point ignition device, Fig. 7 being a corresponding elevation 30 shown partly as a section on the line D D of Fig. 6, while Fig. 8 shows a form of spring blade contact for the low tension interrupter.

In carrying the invention into effect according to 35 one form as applied, for example, to a four-point electrical ignition apparatus fitted to a motor vehicle (see Figs. 1-4), two spindles, *a*, and *b*, are provided side by side and are geared together, for example by the spur wheels, *c*, to run at the same speed, suitable means 40 such as a chain wheel, *d*, or the like on one of the spindles, being provided in the manner usual when an interrupter or the like is to be geared to the motor it serves.

The one spindle, *a*, carries a toothed disk or interrupter, *e*, adapted in connection with a blade contact, *f*, to make and break the low tension circuit, by way of the insulated terminal *u'* of the primary of the coil, *v*, four times per revolution of said spindle, or with motors working with the usual four stroke cycle, four 50 times every two revolutions of the motor shaft; it is of course assumed that the motors served by the complete device, all work on the same shaft. The blade contact, *f*, is mounted on a plate, *h*, or the like which is itself carried by a sleeve, *i*, co-axial with the spindle, *a*; blade 55 plate and sleeve can be adjusted as one piece in relation to the interrupter, *e*, for timing purposes by means

of mechanism to be hereinafter described. A suitable contact, *h*, is also secured to the plate, *h*, and co-acts with the fixed contact, *m*, to insure connection in all working positions of the plate.

The other spindle, *b* carries the rotatable element of the high tension distributor, this rotatable element consisting of a disk or the like, such as *r*, of insulating material, carrying a radial contact arm, *s*, (see Figs. 1 and 2) provided with a knob or button, *t*, disposed preferably at the center of the disk, the button being connected by way of the spring blade *w* to the insulated high tension terminal, *u*, of the coil, *v*, which is earthed. As the radial arm, *s*, revolves, it connects in succession with four fixed contact pieces, *x*, disposed at 90° apart 70 and connected respectively by way of the terminals, *z*, to one of the insulated electrodes of the four sparking plugs or the like it is desired to operate, the other insulated electrodes of each of the sparking plugs being earthed.

The leads from the fixed contact pieces, *x*, to the terminals, *z*, may conveniently pass behind the insulating plate 2, and under the second insulating plate, 3, as indicated, for example, in Fig. 3, in which for illustrative purpose the plate, *h*, has been rotated through 80 a right angle from the position shown in Fig. 1, the space between the plate, 2, and the side of the box, 4, in which the complete device is arranged being then filled with composition.

Connection between the revolving arm, *s*, and the 85 fixed contacts, *x*, is not, however, made direct, but by way of four intermediate pieces, *y*, as shown in detail in Figs. 5 and 5^a. These intermediate pieces are mounted at equal intervals on a carrier, *g*, made of ebonite or other insulating material, the carrier itself 90 being in turn secured to an adjustable sleeve, *i*, co-axial with and surrounding the distributor spindle, *b*, the intermediate pieces, *y*, being always in contact with the fixed contacts *x* and attached to the sleeve, *i*, allowing their position to be adjusted tangentially in 95 connection with the timing of the spark.

It will be understood that the positions of the revolving contact, *y*, and fixed contact, *x*, in Fig. 4, do not correspond precisely with the similar parts of Figs. 1 and 2, but have been brought into the sectional plane 100 of Fig. 4 for convenience of drawing and description in a manner well understood.

The adjustable sleeves, *i* and *j*, on the spindles of the 105 interrupter and distributor respectively, are geared together by the segment spur wheels, *8*, or the like, in Fig. 2, additional segment spur wheels, *9*, one of which is mounted on a rod, *10*, carrying a lever 10^a or the like, being shown as conventional means of operating the sleeves *i* and *j*. The necessary adjustments on the low tension circuit for accelerating or retarding the 110 spark are thus accomplished simultaneously with the corresponding adjustments on the high tension circuit.

The distributor is so arranged in relation to the interrupter that the rotatable contact arm, *s*, of the distributor is opposite one of the high tension contacts when the low tension circuit is completed by the interrupter, the arcs of contact of the high tension circuit being preferably made somewhat larger than those of the low tension circuit so that the makes and breaks may be upon the latter.

Where more than about four cylinders have to be served, the distributor above described is preferably modified so as to avoid a too close proximity of the high tension contacts. In carrying this modification into effect according to one form as shown in Figs. 6 and 7 the intermediate contact pieces, *5*, described above as mounted on the adjustable sleeve, *7*, are in the modified form divided into two sets, *5^a*, and *5^b*, arranged on the carrier, *6*, in a "staggered" or zigzag manner, each set being thus respectively in one of two parallel planes at right angles to the axis of the distributor spindle, so that although in an end view as seen in Fig. 7, the center lines of these contact pieces are separated by arcs of only 60°, nevertheless their actual distances apart may be readily made sufficiently great to safeguard against short circuits. The radial contact arm, *s*, mounted on the spindle is made of sufficient length, as shown in Fig. 6, to reach the more distant set of contacts, *5^b*. The arrangement of the interrupter in this modified form of the invention is the same as that already described above, with the exception that the interrupter, *e*, is replaced by a similar one adapted to make and break the current six times per revolution instead of only four times.

Reference symbols not directly referred to in Figs. 6 and 7 bear the same significance as above.

35 Instead of the ordinary blade contact, *f*, described above in connection with the low tension spindle, for high speeds or when otherwise desirable, I may adopt the form of contact shown in Fig. 8. The spring blade, *f*, is as before mounted on the plate, *h*, but carries a 40 roller, *11*, which co-operates and is in continual contact with the toothed disk, *e* or the like; the makes and breaks then occur at platinum contact points, *12*, or the like, carried respectively by the blade, *f*, and a screw, 13, mounted on the plate, *h*, fixed to the adjustable 45 sleeve, *i*.

The whole apparatus with the exception of the gear wheels, and co-operating parts may be conveniently put up in box form as already described and be arranged on the dashboard, *14*, (see Fig. 2,) of the vehicle 50 or elsewhere.

Having thus described my invention, what I claim as new and desire to secure by Letters Patent is:—

1. In an electrical ignition device, the combination of two rotatable shafts, geared together; an interrupting device operated by one of said shafts and acting to make and break the low tension circuit of an induction coil; a distributing device operated by the other of said shafts and comprising a rotatable contact piece co-acting with a plurality of fixed contact pieces to distribute the induced 55 high tension current to the required sparking points; means for timing the sparks, said means including adjustable elements co-axial respectively with said interrupter and distributor shafts, the element co-axial with said distributor shaft carrying intermediate contact pieces equal in number to said fixed contact pieces and in 60 slidable contact therewith.

2. In an electrical ignition device, the combination of

two rotatable shafts; a casing through a wall of which said shafts pass; means disposed without said casing for gearing together said shafts and disposed within said casing an interrupting device operated by one of said shafts and acting to make and break the low tension circuit of an induction coil; a distributing device operated by the other of said shafts and comprising a rotatable contact piece co-acting with a plurality of fixed contact pieces to distribute the induced high tension current to the required sparking points; means for timing the sparks, said means including adjustable sleeve elements co-axial respectively with said interrupter and distributor shafts and passing through said casing wall; 70 segmental spur wheels disposed without said casing and gearing together said sleeve elements together with intermediate contact pieces disposed within said casing and carried by the sleeve element co-axial with said distributor shaft, said intermediate contact pieces being 75 equal in number to said fixed contact pieces and in slidable contact therewith.

3. In an electrical ignition device, the combination of two rotatable shafts geared together; an interrupting device operated by one of said shafts and acting to make and break the low tension circuit of an induction coil; a distributing device operated by the other of said shafts and comprising a rotatable contact piece co-acting with a plurality of fixed contact pieces to distribute the induced high tension current to the required sparking points; means for timing the sparks, said means including adjustable elements co-axial respectively with said interrupter and distributor shafts, the element co-axial with said distributor shaft carrying a contact piece in slidable contact with a fixed contact piece.

4. In an electrical ignition device, the combination of two rotatable shafts geared together; an interrupting device operated by one of said shafts and acting to make and break the low tension circuit of an induction coil; a distributing device operated by the other of said shafts and comprising a rotatable contact piece co-acting with a plurality of fixed contact pieces to distribute the induced high tension current to the required sparking points; means for timing the sparks, said means including adjustable elements co-axial respectively with said interrupter and distributor shafts, the element co-axial with said distributor shaft carrying a contact piece in slidable contact with a fixed contact piece, and the element co-axial with said interrupter shaft carrying a contact point and a spring blade provided with a co-acting contact point, said spring blade carrying a roller co-acting with said interrupting device.

5. In an electrical ignition device, the combination of two rotatable shafts geared together; an interrupting device operated by one of said shafts and acting to make and break the low tension circuit of an induction coil; a distributing device operated by the other of said shafts and comprising a rotatable contact piece co-acting with a plurality of fixed contact pieces arranged in a zig-zag manner to distribute the induced high tension current to the required sparking points together with means for timing the sparks, said means including adjustable elements co-axial respectively with said interrupter and distributor shafts, the element co-axial with said distributor shaft carrying intermediate contact pieces also arranged on a zig-zag manner, said intermediate pieces being equal in number to said fixed contact pieces and in slidable contact therewith.

6. In an electrical ignition device, the combination of two rotatable shafts geared together; an interrupting device operated by one of said shafts and acting to make and break the low tension circuit of an induction coil; a distributing device operated by the other of said shafts and comprising a rotatable contact piece co-acting with a plurality of fixed contact pieces to distribute the induced high tension current to the required sparking points; means for timing the sparks, said means including adjustable elements co-axial respectively with said interrupter and distributor shafts, the element co-axial with said distributor shaft carrying intermediate contact pieces equal in number to said fixed contact pieces and in slidable contact therewith; a casing containing all the

5 Electrical portions of the complete device above set forth together with connections from said fixed contacts to an equal number of terminals fixed on the outside of said casing, said connections being separated from the rotatable elements within said casing by a fixed partition.

- 6 7. In an electrical ignition device, the combination of two rotatable shafts geared together; an interrupting device operated by one of said shafts and acting to make and break the low tension circuit of an induction coil; a 15 distributing device operated by the other of said shafts and comprising a rotatable contact piece co-acting with a plurality of fixed contact pieces to distribute the induced high tension current to the required sparking points;
- 10

means for shielding the spaces, said means including adjustable elements co-axial respectively with said interrupter and distributor shafts, the element co-axial with said distributor shaft carrying a contact piece in slidable contact with a fixed contact piece and contacting with said rotatable contact piece.

8 In witness whereof I have hereunto set my hand in 20 presence of two witnesses.
